CLAIM

The ornamental design for a display panel with the animated graphical user interface, as shown and described.

DESCRIPTION

1. Display panel with the animated graphical user interface
- 1.1 : First image in a sequence
- 1.2 : Second image in a sequence
- 1.3 : Third image in a sequence
- 1.4 : Fourth image in a sequence
- 1.5 : Fifth image in a sequence

The broken lines in the reproductions form no part of the claimed design; the design is a display panel with the animated graphical user interface, in which the appearance of the animated image sequentially transitions from the images shown in reproductions 1.1 to 1.5. The process or period in which one image transitions to another image forms no part of the claimed design.
